UNITED STATES PATENT OFFICE.

EUSTACE CAREY, HOLBROOK GASKELL, JR., AND FERDINAND HURTER, OF WIDNES, COUNTY OF LANCASTER, ENGLAND.

PROCESS OF MAKING SODIUM SULPHITE.

SPECIFICATION forming part of Letters Patent No. 321,341, dated June 30, 1885.

Application filed May 20, 1885. (No specimens.) Patented in England June 26, 1884. No. 9,458.

To all whom it may concern:

Be it known that we, EUSTACE CAREY, HOLBROOK GASKELL, the younger, and FERDINAND HURTER, alkali manufacturers, subjects of the Queen of Great Britain and Ireland, and of the Republic of Switzerland, respectively, and residing at Widnes, in the county of Lancaster, England, have jointly invented certain Improvements in the Manufacture of Sulphite of Soda, (for which we have made application in Great Britain, No. 9,458, dated June 26, 1884,) of which the following is a specification.

Our invention has for its object the manufacture at a low cost of sulphite of soda suitable for use in the manufacture of paper or for other purpose to which it may be applicable. According to our said invention we employ in the said manufacture of sulphite of soda "salts," meaning thereby monohydrated carbonate of soda. The said salts may, for the purposes of our invention, be obtained in any suitable way—such, for example, as by evaporation by heat of those solutions of soda named in the specifications of the British Letters Patent granted to Eustace Carey, Holbrook Gaskell, Jr., and Ferdinand Hurter, on the 18th day of July, 1879, No. 2,939, the 11th day of January, 1881, No. 608, and the 17th day of March, 1881, No. 1,161, the said alkaline solutions having been first purified by the processes named in the specifications of the said Letters Patent, or for certain purposes where color and purity are not of importance the salts may be those obtained in the Le Blanc process by the evaporation by heat of the solution of crude carbonate of soda, known as "vat-liquor" or "tank-liquor," or they may be salts obtained by the evaporation by heat of other solutions of carbonate of soda. To the said salts, by whichever method obtained, we add, if necessary, a small quantity of water or of steam and expose the said salts in suitable vessels to the action of sulphurous-acid gas obtained in any convenient way—for example, by burning sulphur or pyrites. This treatment of the salts with sulphurous-acid gas is continued until they are sufficiently converted into sulphite of soda, which is applicable for use in

the manufacture of paper or other purpose where it is not necessary that the sulphite should be of a high test, as although the said sulphite is very readily and cheaply manufactured by the process constituting our invention, as hereinbefore described, it will not be uncontaminated with bicarbonate of soda or other impurities, but these impurities will not render the sulphite of soda unsuitable for use for certain purposes—such, for example as for employment in the manufacture of paper.

We do not limit ourselves to any particular form of apparatus in which to carry on the process according to our invention, as any suitable apparatus may be employed for this purpose; but we will describe a form which is suitable for the purpose. It is shown in the annexed sheet of drawings in side elevation in Fig. 1, and elevation in Fig. 2, and plan in Fig. 3. The iron cylinder A (which, if sulphite of soda of great purity is required, may be lined with lead) is capable of being rotated upon a horizontal axis. The cylinder is provided with hollow trunnions or axes supported by and capable of turning in bearings *a*, carried by a suitable frame-work, *a'*. The hollow trunnion at one end of the cylinder A is used for admitting sulphurous-acid gas, and that at the other end for permitting the exit of excess of sulphurous acid, of carbonic acid, of nitrogen, and of moisture. The said hollow trunnions are continued by pipes entering into the interior of the cylinder and there turned at or about right angles to the axis of the cylinder A, as shown at *b*, for the purpose of avoiding the lodgment therein of solid material, and the consequent stoppage of the free passage of the gas into or from the cylinder A.

We find it advisable to have an aperture in the cylinder A and in the exit-pipe C, as shown at *e e*, which apertures can be closed air-tight in any convenient manner, and through the said aperture which is in the cylinder, the part *b* of the exit-pipe C, which is in the cylinder A, may be cleaned easily and freed from dust, which is sometimes deposited there.

Having described a form of apparatus suited for the purposes of our invention, we will pro-

ceed to describe the method of working which we find advantageous. The charge of salts is introduced into the cylinder A through an aperture provided for that purpose, which is then closed. The cylinder is made to revolve slowly by any suitable means—for example, by means of a pulley, F, and spur-gearing G driven by any suitable motor. We find from two to six revolutions of the cylinder per minute are sufficient. Sulphurous-acid gas is admitted into the interior of the cylinder A by the pipe y, and the sulphurous acid is absorbed by the charge.

The progress of the operation may be ascertained by withdrawing and testing a sample from time to time. We find that when a sample contains from thirty-six to forty per cent. of sulphurous acid, the product practically answers all the purposes of a monosulphite of soda, and the process is then stopped and the charge withdrawn. If strong sulphurous acid be used, such as is obtained by treating sulphuric acid with coke or with sulphur, one such cylinder A is sufficient, but when sulphurous acid mixed with nitrogen is used, as it is when obtained by the combustion in atmospheric air of sulphur or pyrites or sulphurated hydrogen, then the absorption is not complete in one cylinder, and the gases leaving the cylinder A by the exit-pipe C still contain sulphurous acid. These gases may be passed through one or more cylinders similarly constructed, and so arranged that any one of them may be connected directly to the source of supply of sulphurous acid, or be made to receive the gases from another cylinder of the series, or be isolated for discharging and charging, as required; or the gas escaping from the cylinder A may be passed into a sulphuric-acid chamber. If the sulphurous acid be obtained by the combustion of pyrites or brimstone, it is advisable to pass it through a dust-chamber before allowing it to enter the cylin-

der A, so that any dust may be first deposited. If the sulphite of soda be desired of great purity, it is also necessary to wash the sulphurous acid by passing it through a small tower, U, Fig. 3, lined with lead and filled with coke. The gas passes in an upward direction through the tower and meets a very small stream of hot water. When the gas has thus been washed it must be dried. For this purpose the gas passes in an upward direction through a similar tower, V, filled with coke, where the gas meets a stream of sulphuric acid which absorbs the moisture; but when great purity of the sulphite of soda is not required we omit the washing and drying of the sulphurous-acid gas, except when it is obtained by the combustion in air of sulphurated hydrogen, in which case the gases must be dried. When the cylinders are worked in series, it may be found necessary to dry the gas on passing from one cylinder to the next. For this purpose the gas may be passed through a coke-tower, V, as before described, which may be placed between the cylinders, or the gas may be dried in any other convenient manner.

Having now particularly described and ascertained the nature of our said invention and in what manner the same is to be performed, we declare that what we claim is—

The manufacture of sulphite of soda by exposing salts to the action of sulphurous-acid gas, substantially as hereinbefore described.

In testimony whereof we have signed our names to this specification in the presence of two subscribing witnesses.

EUSTACE CAREY.
HOLBROOK GASKELL, JR.
FERDINAND HURTER.
